UNITED STATES PATENT OFFICE.

ERNEST M. RODEBAUGH, OF LONG BOTTOM, OHIO.

CARBID-FEED FOR ACETYLENE-GENERATORS.

1,221,475.

Specification of Letters Patent.

Patented Apr. 3, 1917.

Original application filed March 27, 1914, Serial No. 827,697. Divided and this application filed May 29, 1915. Serial No. 31,211.

To all whom it may concern:

Be it known that I, ERNEST M. RODEBAUGH, a citizen of the United States, residing at Long Bottom, in the county of Meigs and State of Ohio, have invented a new and useful Carbid-Feed for Acetylene-Generators, of which the following is a specification.

This invention relates to carbid feeds for acetylene generators and is more specially a division of patent No. 1,156,495, issued to me on October 12, 1915.

One of the objects of the invention is to provide means controlled by the rise and fall of the bell of the gasometer for closing and opening a valve controlling the discharge opening of the carbid container so that, each time the bell descends due to the scarcity of gas therein, the discharge of carbid will be permitted whereas, during the rise of the bell due to the generation of gas, the said opening will be closed automatically.

A further object is to provide means for deflecting the carbid during its discharge into the gasometer.

Another object is to provide means whereby when the feed opening in the carbid holder is uncovered or its closure removed, the escape of carbid into the body of the gasometer by way of the feed gate will be automatically cut off, thus reducing danger of explosion or waste of gas.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:-

Figure 1 is a vertical section through a portion of an acetylene generator and showing the present improvements combined therewith.

Fig. 2 is a section on line A—B Fig. 1.

Fig. 3 is a section on line C—D Fig. 1.

Fig. 4 is a section on line E—F Fig. 1.

Referring to the figures by characters of reference 1 designates a portion of the main

receptacle of the generator, and 13 designates a portion of a bell designed to work upwardly and downwardly within said receptacle.

An opening 21 is provided concentrically of the bell 13 at the top thereof and fitting thereunder is the funnel shaped end 22 which coöperates with the carbid receptacle 23. The funnel is therefore disposed to project within the bell 13. A filling opening 24 is provided in the top of the receptacle 23 and is controlled by a screw plug 24'.

A valve actuating rod 25 is disposed within the carbid holder 23 so that its upper end by means of the spring 26 is held in engagement with the under side of the plug 24' which acts as a means for limiting the upward movement of the rod, the removal of the plug 24' permitting the rod to be moved upwardly by the spring 26. Thus the pivoted closure 28, which is pivotally connected to the rod 25, is elevated and closes the spout 29 during the filling of the receptacle 23 with carbid. Then when the cap 24' is placed in position, the rod 25 is depressed and the closure 28 assumes the position as shown in the drawings, so that the carbid may be directed through the spout 29 into the generating chamber.

During the filling of the carbid holder receptacle 23, it is essential that the bell 13 be maintained in a stationary position and in order to permit this, a frame 33 is provided and is connected to the member 1, projecting thereabove and carrying the sleeve 32 for the reception of the stem 31 which is connected to the upper end of the carbid receptacle 23, said stem 31 being held in an elevated position by a pivoted arm or clutch 32 which holds and locks the bell and the carbid receptacle in the desired elevated position during the removal of the cap 24' and the recharging of the carbid holder 23.

In order to provide an automatic means for feeding the carbid from the outlet end 100 of the spout 29 due to the lowering of the bell 13 and to cut off the supply when the bell has been elevated to the proper distances, a pin 35 forms a pivot for the lug 34 of the swinging member 36, said member 36 being disposed to swing below and close to the outlet 29 of the funnel 22 when the bell 13 is at its highest elevation or at

its adjusted elevation. The lowering of the bell causes the lower end of the rod 38 to engage the bottom of the receptacle 1 and thus depresses the blade end 37 of the member 36 to open the outlet 29, the carbide therefrom being directed upon the blade 37 which in turn directs the same into the bottom portion of the main receptacle or casing 1 of the generator. As soon as the gas has 10 been generated sufficiently due to the introduction of the carbide within the water of the generator, the bell 13 is elevated and the rod 38 disengaged from the lower end of the receptacle 1, so that the parts are in 15 the position as shown. The weight of the rod 38 will be sufficient to automatically close the member 36 against the bottom end of the spout as soon as the rod 38 is lifted out of engagement with the bottom of the 20 generator or casing 1. In order to render this action of the cut of member 36 adjustable, an extension end 39 is fitted upon the lower end of the rod 38, the same being preferably screw threaded so as to be readily 25 adjusted when desired.

What is claimed is:—

In an acetylene generator, a carbide holder having an outlet opening in the bottom thereof and a filling opening in the top thereof, a yieldingly supported valve hinged within the outlet, a rod pivotally connected to and supported by said valve, said rod extending upwardly into the filling opening, a closure removably mounted in the filling opening and having a recess for the 35 reception of the upper end of the rod, said closure holding the rod pressed downwardly and the valve normally in open position, and a spring within the carbide holder and connected to the bottom of said carbide holder and to the rod, for exerting an upward pull upon the rod when released from engagement with the closure.

In testimony that I claim the foregoing as my own, I have hereto affixed my signature in the presence of two witnesses.

ERNEST M. RODEBAUGH.
